UNITED STATES PATENT OFFICE.

CLARENCE E. BECHTOLT, OF DAYTON, OHIO, ASSIGNOR TO THE RECORDING AND COMPUTING MACHINES COMPANY, OF DAYTON, OHIO, A CORPORATION OF OHIO.

FARE-BOX.

1,252,651.

Specification of Letters Patent.

Patented Jan. 8, 1918.

Application filed December 30, 1916. Serial No. 139,917.

To all whom it may concern:

Be it known that I, CLARENCE E. BECHTOLT, a citizen of the United States, residing at Dayton, in the county of Montgomery and State of Ohio, have invented certain new and useful Improvements in Fare-Boxes, of which the following is a specification, reference being had therein to the accompanying drawing.

- 10 My invention relates to fare boxes, and in particular to a means for separating coins and tickets from one another which are deposited indiscriminately through the mouth of said fare box.
- 15 The object of my invention is to separate the coins and tickets. In particular it is my object to so sift and separate the coins from the tickets that it may be done both rapidly and economically and that the tickets may 20 be retained in the sifter or separator in such a way that they can be disposed of by deposit in a receptacle or by canceling and then depositing them in said receptacle.

It is my object to prevent the tickets 25 from following the coins.

In the accompanying drawings, Figure 1 is a side elevation of a section of a fare box employing my separator or sifter; Fig. 2 is a top, plan view of the separator itself; 30 Fig. 3 is a cross section on the line *a* *a* of Fig. 2 at right angles to the longitudinal axis of Fig. 2; and Fig. 4 is a bottom plan view of the separator.

In Fig. 1 the entire fare box is shown assembled in sufficient detail to indicate the general relation of the separator to the rest of the mechanism. The tickets and coins enter at the top of the fare box at the point 1 and rest upon the inspection plates 2, 2 before dropping into the hopper, of which 35 the sifter body 3 forms the bottom. Upon the operation of the handle 4 by a suitable train of gears, cams and levers the sifter body 3 is placed generally across the bottom of the hopper 5 and the inspection plates 2, 2 are operated at the middle and depressed so that the coins and tickets can 40 fall upon the body of the separator. Upon the continued turning of the crank 4 through 45 certain cam and gear mechanism, together with the attendant levers which it is not necessary to describe in this instance, the separator is swung back and forth on the pivotal point 6 so that it assumes varied po-

sitions, shaking the coins and tickets resting upon it with the result that the coins fall through the apertures 7, 7 into a suitable receptacle below the separator. The tickets in this particular fare box are retained on the body of the separator designated as 3 and finally the body of the separator is brought in close proximity to the periphery of the drum 8 which serves to pick up the tickets and carry them under the inking and canceling roller 9 and thence 55 into the chute 10' where the canceled tickets are carried into a suitable receptacle.

I do not mean to confine myself to any combination in which the separator is to be used solely for the purpose of sifting the 70 tickets to be canceled as the tickets can be disposed of in many ways, but my primary object is to separate the coins from the tickets in such a way that the tickets will not be mutilated by such a means as 75 the ribbed drum and will still be kept from following the coins.

In order to accomplish this object I have placed a series of arches 10, 10, one over each aperture 7. These arches are of a peculiar configuration, in cross section triangular with the apex of the triangle adjacent the aperture through which the coins descend. This arch prevents the ticket from dropping through the aperture 7 while at 80 the same time it permits the coin to slip by. The apertures usually are slightly larger than the size of the maximum coin handled and often times wider than the width of the ticket. This arch or bridge spanning the 85 aperture prevents the ticket from getting through the opening completely, while the sharp edge permits the coin to readily slide by the obstruction.

In my separator I have provided a steel 95 guard plate 11 as a lining for the separator which is usually made of a soft metal like aluminium in order to secure a very light construction which can be readily handled and operated.

In Fig. 2 I have shown a top, plan view of the separator *per se*. The bridge or arch 10, 10 can be seen below the orifice spanning it. 12 indicates the apex of the triangular formation of the rib or arch. 13 represents 100 a lip or rib running around a portion of the periphery of each orifice.

Figs. 3 and 4 are merely additional views

of the same separator and do not necessitate any additional description. Like numerals designate like parts.

While I have shown and described one embodiment of the invention it will be understood that this has been chosen for the purposes of illustration only and that I do not desire to be limited to the details of construction shown and described, for obvious 10 modifications will occur to a person skilled in the art.

Having thus fully described my invention, what I claim as new and desire to secure by Letters Patent, is:

- 15 1. In a separator, a curved body with a hole therein, an arch under said hole, whereby coins are allowed to escape but tickets are prevented from doing so.
- 20 2. In a separator, a curved body with a hole therein, an arch extending longitudinally from one edge of said hole to the other edge, whereby coins are allowed to escape but tickets are prevented from doing so.
- 25 3. In a separator, a curved body with a hole therein, an arch extending longitudinally from one edge of said hole to the other edge, said arch being triangular in cross section with the apex of the triangle adjacent to the hole, whereby coins are allowed to escape but tickets are prevented from doing so.
- 30 4. In a separator, a curved body with a series of holes therein, a series of arches spanning said holes, whereby coins are allowed to escape but tickets are prevented from doing so.
- 35 5. In a separator, a curved body with a series of holes disposed in pairs, one behind the other, an arch for each hole where-

by coins are allowed to escape but the tickets are prevented from doing so.

6. In a separator, a curved body with an orifice therein, and means co-operating with said orifice and said curved body to prevent the escape of tickets, whereby coins are allowed to escape but tickets are prevented from doing so.

7. In a separator, a curved body with an orifice therein, means on one side of said curved body under said orifice to prevent the escape of tickets, whereby coins are allowed to escape but the tickets are prevented from doing so.

8. The combination, with a fare box having a hopper provided with coin sifting devices therein, of a curved body with a hole therein, an arch extending longitudinally from one edge of said hole to the other on one side of said curved body, whereby coins are allowed to escape but tickets are prevented from doing so.

9. In a separator, a sifting plate provided with a plurality of openings through which coins may pass, and guards mounted below said openings to prevent the passage of tickets.

10. In a separator, a curved body, a hole therein for the passage of a coin, an arch for said hole to prevent the passage of a ticket therethrough, another hole in said body co-operating with a pin passing therethrough to dislodge any coins adjacent said second-mentioned hole, whereby the coins are allowed to escape but tickets are prevented from doing so.

In testimony whereof, I affix my signature.

CLARENCE E. BECHTOLT.
